UNITED STATES PATENT OFFICE

JAMES P. FISHER, OF BARTLESVILLE, OKLAHOMA, BENJAMIN GREENFIELD, OF JACKSON HEIGHTS, NEW YORK, AND NOBLE M. HUTCHINSON, OF OIL HILL, KANSAS, ASSIGNORS TO DOHERTY RESEARCH COMPANY, OF NEW YORK, N. Y., A CORPORATION OF DELAWARE

GAS-BURNING DEVICE

Original application filed January 10, 1924, Serial No. 685,319. Divided and this application filed September 11, 1928. Serial No. 134,806.

This application is a division of our co-pending application filed January 10, 1924, Serial No. 685,319, and the invention herein disclosed relates to improvements in gas burning devices. One of the objects of the invention is to provide a gas burner which will function efficiently at relatively low gas pressure and which will produce a soft rolling flame under normal conditions of operation. 10 One of the prime requisites of an efficient gas burner is that the gas and air be intimately mixed in correct proportions for complete combustion,—a requisite that has not been easy of attainment with gas at low pressure. 15 The apparatus of the present invention, however, enables a proper air-gas mixture to be obtained with gas at low pressure and additionally gives a soft rolling flame which completely fills the firebox as contrasted with the 20 blast-like flame of poorly designed burners which if allowed to impinge on the inside of the firebox will cause buckling of the walls, loosening of the stay bolts, and other boiler troubles. 25 The burner arrangement according to the present invention comprises a relatively large number of gas nozzles or jets above each of which is a short mixing tube. The flow of gas produces an aspirating action which draws 30 primary air into the mixing tubes where the air and gas are formed into a combustible mixture. Secondary air for complete combustion is drawn into the combustion space above the mixing tubes by way of openings between the 35 mixing tubes.

For a more complete understanding of the invention reference is made to the following detail description in connection with the accompanying drawing wherein the preferred 40 form of the invention is shown.

Referring to the drawing,

Fig. 1 is a plan view of the improved burner construction showing the burner as arranged 45 within a boiler firebox which latter is shown in horizontal cross section, and also showing an air box or conduit through which air passes on its way to the burner.

Fig. 2 is a vertical section on line 2—2 of 50 Fig. 1 showing among other things the rela-

tive relation between the mixing tubes and gas nozzles.

Fig. 3 is a plan view of one of the castings which go to make up the mixing tube set.

Fig. 4 is a side elevation of the casting 55 shown in Fig. 3.

The improved burner is positioned in any suitable manner at the bottom opening of a boiler firebox generally indicated at 10 or in the manner hereinafter more fully described. 60 The mixing tubes forming part of the burner are generally indicated at 12 and the gas nozzles at 14, the latter being positioned below the former and in axial alinement therewith. The mixing tubes 12 are preferably 65 arranged in parallel rows there being provided between adjacent rows a slot or opening 16 through which secondary air for combustion may enter the combustion space above the mixing tubes as will presently more fully 70 appear.

Each row of mixing tubes is preferably 75 formed as part of a cast bar or plate 18 having end lugs as at 20 for securing the casting to a frame 22 which is positioned within the bottom opening of the boiler firebox in any suitable manner. The castings 18 are arranged side by side in spaced relation, the spaces between the casting constituting the slots or openings 16 for secondary air as previously 80 mentioned. Figs. 3 and 4 show the actual details of constructions of the mixing tube castings 18.

The gas nozzles 14 extend from a header 24 which is supplied with gas by a pipe 25. The 85 tips of the gas nozzles are positioned somewhat below the bottom openings of the mixing tubes 12 which latter are of relatively large diameter and of short length. A pilot burner 26 is positioned at any suitable point 90 on the gas pipe therefor being arranged in any suitable manner or as indicated at 28.

The air for combustion purposes flows to the burner through a flue or air duct generally indicated at 30. This flue opens onto the bottom of the firebox opening, the flow of air through the flue being controlled by dampers 95 32 and 34. Damper 32 is set in such a manner that the proper amount of air is supplied to the burner when the latter is being supplied 100

with the maximum amount of gas. Damper 34 on the other hand is operated to regulate the air supply in accordance with variations in gas feed in a manner disclosed in the co-pending application above referred to.

5 The frame 22 within which the mixing tubes are located is preferably surrounded by a refractory member 36 to protect that edge of the frame which is exposed to the 10 heat of the burner. Fire-clay or the like 38 may be inserted between the sides of the firebox opening and the refractory member 36 and frame 22 to make an air tight joint therebetween.

15 As previously indicated, the gas issuing from the gas nozzles 14 is directed into the center of the mixing tubes and draws air into the tubes to form a combustible mixture, which issues from the upper ends or discharge 20 ports of tubes 12. Secondary air is induced to flow through the passages or ports 16 between the rows of mixing tubes and into the combustion space above the mixing tubes to complete combustion, the air flow for the 25 burner being regulated by dampers placed in the air flue through which air flows to the burner. The amount of secondary air flowing into the combustion space is of course determined by the size of the openings or slots 30 between the mixing nozzle rows. It has been found that when the area of the secondary air passages is less than the cross-sectional area of the mixing nozzles, the best results are obtained. A burner constructed and arranged 35 as specified enables gas at low pressures to be properly mixed with air for combustion purposes and enables a soft rolling flame to be obtained within the firebox.

Although the burner of this invention has 40 been illustrated and described as applied to a steam boiler, it is to be understood that it is applicable with equal facility to a hot-water, hot air or other furnace or heating device.

What is claimed is:

45 1. In a gas burner, the combination of a plurality of uniformly shaped narrow bars each having a plurality of holes formed therein constituting open ended primary air-gas mixing tubes extending therethrough, said bars being arranged in spaced parallel relation to form relatively narrow passages therebetween for the passage of secondary air from adjacent the inlet to the outlet ends of said tubes, and gas jet members spaced from the bars and co-axial with the holes therein for directing the gas and inducing primary air into said tubes.

50 2. A burner unit for gas heating apparatus comprising a gas burner having a plurality of spaced orifices in its combustion face, each of said orifices comprising an outlet from a primary air-gas mixing device, secondary air passages formed in the burner having an outlet located in the combustion face of the burner closely adjacent to each of

the air-gas orifices, and a damper controlled duct arranged to supply air to said mixing device and to said air passages.

55 3. A burner unit for gas heating apparatus comprising a gas burner formed with a plurality of spaced orifices arranged in spaced rows in its combustion face, each of said orifices forming the outlet of one of a plurality of spaced primary air-gas mixing tubes, secondary air passages with discharge 70 ports in the combustion face of the burner formed in the spaces separating adjacent rows of said orifices and mixing tubes, and a damper controlled duct arranged to supply air at a controlled rate to said mixing tubes 75 and air passages.

80 4. A burner unit for gas-heating apparatus comprising a multi-apertured gas burner adapted for setting in a furnace fire-box opening, some but not all of the burner apertures being arranged for the delivery of a primary air-gas mixture to the combustion face of the burner, an air supply duct open at its inlet end to the outer air, said burner forming a perforate closure for the outlet 85 end of the duct, and means for supplying gaseous fuel to the air-gas apertures, the remainder of said burner apertures being arranged for delivery of secondary air from 90 said air duct to the burner face adjacent each 95 of the air-gas apertures.

100 5. A burner unit for gas heating apparatus comprising a gas burner formed with a plurality of closely spaced air-gas delivery ports and air discharge openings in its combustion face, an air supply duct, said burner forming a perforate closure for the outlet end of said duct, a gas and air mixing device communicating with each of same air-gas ports, passages in the burner connecting said air duct 105 and said discharge openings, and a damper arranged to control the supply of air to said discharge openings and to said mixing device.

110 6. In a gas burner, in combination, a plurality of gas-air mixing tubes, said tubes being spaced to provide secondary air passages therebetween, a gas jet spaced from and axially centered in the inlet end of each mixing tube, said tubes and passages terminating 115 respectively in closely spaced flame ports and air discharge openings in the combustion face of the burner, and a damper controlled duct arranged to supply air to the inlet ends of the said tubes and passages.

120 In testimony whereof we have affixed our signatures.
